[57] CLAIM

The ornamental design for an anthuriums packing board or similar article, substantially as shown and described.

DESCRIPTION

FIG. 1 is a top plan view of an anthuriums packing board showing my new design;
FIG. 2 is an edge view looking from the left of FIG. 1;
FIG. 3 is a top perspective view in a folded position;
FIG. 4 is an enlarged fragmentary perspective view of the neck portion thereof in a partially folded position;
FIG. 5 is a top plan view in a folded position with packed flowers and a bag being shown in broken lines for the purpose of illustrating environmental use only.
The dash lines on the neck in FIG. 1 represent fold lines.
